INTERNAL COMBUSTION ENGINE

Allen Miller Fish, Joliet, Ill.

Application June 14, 1930. Serial No. 461,243

9 Claims. (Cl. 123—190)

This invention relates to internal combustion engines and aims to provide an improved multiple-cylinder gas motor having the advantages of both the V-type and vertical "straight" motors without the disadvantages of either. Increased power with reduced size and a lower cost of production are important objects of the invention.

It will be best understood by description with reference to the attached drawings illustrating one practicable embodiment thereof in a four-cylinder engine.

In said drawings:

Fig. 1 is a front-end view of the engine in transverse section;

Fig. 2 is a left-side view of the same in longitudinal section;

Fig. 3 is a transverse section of the upper part at the point of intake-manifold connection;

Fig. 4 is a similar view at the point of exhaust-manifold connection;

Fig. 5 is a longitudinal section of a rotary controlling valve;

Fig. 6 is a longitudinal section of the crank-shaft;

Fig. 7 is a plan view of a lever-element coordinated with said shaft; and

Fig. 8 is a plan view of a block for an eight-cylinder engine embodying the invention.

It may facilitate understanding to state at the outset that the motor or engine of this invention is operable on the "lever" principle and has a single rotary valve controlling the intake and exhaust of the cylinders irrespective of the latter's number. It may therefore be characterized as a combined lever and rotary-valve type motor.

The illustrative engine of four-cycle form comprises a block or casting 9 having vertical cylinder bores 10 arranged in adjacent longitudinal rows of equal number on opposite sides of a central plane. This block also has a horizontal bore 11 between the rows of cylinders and substantially below the top ends or combustion spaces thereof to receive the rotary intake-and-exhaust valve later described. Passages 12 leading from opposite sides of said bore to the top of the block abreast the cylinder bores (see Figs. 1 and 2) provide combined intake-and-exhaust ports for the cylinders when the cylinder-head with combustion chambers opening thereinto is affixed to the block. Between these passages for each opposing pair of cylinders, a space 13 open to said bore from above provides for communication with the intake-manifold, while outbounding or end spaces 14 also open to said bore from above provide for communication with the exhaust-

manifold (see Figs. 3 and 4). The usual water-cooling jacket 15 is provided, with that portion of the block which lies between the rows of cylinders forming an extra large water space partially surrounding the bore for the rotary valve. 60

Said block is bolted onto a supporting crank-case 16 having the usual oil-sump or pan 16^a with drain-plug 17. This case is somewhat wider in proportion to its height than the ordinary crank-case for a reason to hereinafter appear, 65 and is advantageously formed of a light thin-wall material reinforced by ribbing or brace-strips as represented at 18. It rests of course in a bed or cradle such as the frame of an automobile. Bearings 19 at opposite ends of the case 70 provide journalment for a crank-shaft with axis in the aforesaid plane parallel to the valve bore and rows of cylinders above.

The crank-shaft 20 is much shorter than allowable in a "straight" type motor of the same 75 number of cylinders and in this instance has a single throw 20^a counterbalanced to eliminate vibration. Only two throws are required in an eight-cylinder engine and three in a twelve-cylinder engine and so on for each additional multiple of four. The shaft is therefore subject to less torsion and may be considerably lighter than in the ordinary engine, even of the V-type where the throws are in number only one-half that of the cylinders. Of course the shaft may have 80 more than one throw, or one for each cylinder may if desired be arranged in degree relation as in the ordinary motor. In the latter case however, the pistons will travel separately instead of in pairs as in this case, so that the rotary 85 valve must be ported and synchronized to fire and exhaust the cylinders accordingly. An oil channel 21 provides for lubricating the bearings of its throw and the latter may advantageously be bored for greater lightening as shown in Fig. 90. 95

The forward-end of the shaft carries a timing-chain gear or sprocket 22 and is adapted for hand cranking as customary, while its rear end carries a fly-wheel or clutch-element 23 with which a starter-motor may be connected if desired. 100

Onto the single throw of the crank-shaft are fitted the ends of pitman-rods or levers 24 in number corresponding with the number of cylinders, or one for each pair of cylinders as in the 105 illustrative engine. These rods extend oppositely therefrom in pairs horizontally disposed with the opposite end of each under a cylinder, or in single pieces for each pair with their opposite ends midway therebetween as in this instance. Thus 110

they may be formed in unitary pairs or separately as preferred and are connected with said throw in the ordinary manner of connecting piston-rods to crank-shafts. The arrangement provides 5 for the pistons in adjacent cylinders at opposite sides of the central plane to travel in pairs, with two at one side moving up as two at the other side move down. This arrangement is carried out in engines of additional cylinders, such as 10 eight or twelve where only one crank-shaft throw is provided for each group or multiple of four as above indicated, except that the throws are then disposed in a relation to give overlap travel or different work moments to the several pairs of 15 pistons and so smooth out the engine's performance.

The aforesaid pitman-rods have opposite end connection with the shorter arms of bell-crank levers 25 mounted on shafts 26 at opposite sides 20 of the crank-case. These bell-crank levers may be separate or formed together as a unit as shown in Fig. 7. They may be loose to rock on said shafts or keyed thereto as by casting in one piece therewith and the latter made rockable as preferred. Brackets 27 serve to support or journal the shafts.

To the longer arms of said bell-crank levers are connected the piston-rods 28 of pistons 29 working in the cylinders. Oil-feed lines (not 30 shown) are extended through the lever connections to lubricate the pistons and cylinder walls in the usual way.

By this organization, the pistons are made to 35 operate on the crank-shaft in a horizontal plane, or in other words, their driving force is applied to said shaft from opposite sides rather than from directly above. This affords several advantages over the ordinary types of engines, viz:

First.—The crank-shaft is "pulled" around in 40 a double action from the sides instead of pushed around from above.

Second.—The piston stroke may be longer since 45 the bell-crank levers instead of the crank throws control their stroke limits.

Third.—The wall-thrust is greatly reduced because the piston-rods swing less from the vertical. This swing beyond vertical amounts to only five or six degrees, whereas it amounts to fifteen or more in the ordinary engine. Accordingly, there 50 is less friction and less heat generated in the cylinder walls and therefore less wear on the latter.

Fourth.—The translation of thrust cushions "pounding action" on the crank-shaft, since the bell-crank levers receive the direct thrust and apply the force horizontally at opposite sides of the crank-shaft with a cushioning effect.

Fifth.—The pistons work throughout approximately the full downward stroke and the exhaust need not open before bottom center is reached, whereas the exhaust in the ordinary engine opens well before bottom center with consequent waste of power.

Sixth.—The mechanical advantage is greater 65 in the last quarter of the working stroke due to piston travel under conditions the reverse of those in the ordinary engine. In the ordinary engine the mechanical advantage is greater in the first quarter of the working stroke when the pressure force of ignited charge is greatest. This is due to greater travel of the piston in the first quarter of the working stroke than in the second. In the present instance however, the mechanical advantage is less in the first quarter of working stroke than in the second, so that the mechanical

advantage is less when the force is greatest and greater when the force is less. This tends to make the torque the same throughout the working stroke and produces a smoother operation of the engine because of the steady continuous pull instead of a hammer-like blow on the crank-shaft. In an eight or twelve cylinder motor of this construction moreover, the power impulses will be more overlapping.

The valve received by the bore (11) between the parallel rows of cylinders comprises a cylindrical body 30 fitting closely therewith as result of a slight tapering of both correspondingly. Journal-ends 30^a thereof rotate in bearings 31 housed within the engine block. A spring 32 at its rear serves to exert an axial moving pressure to maintain clearance. A gear or sprocket 33 on its forward end imparts rotation thereto at half the crank-shaft speed through the medium of a timing-chain 34 running over the aforesaid sprocket (22) on the latter. Another gear (not shown) advantageously serves to tension this chain and also drive a distributor and oil-pump assembly.

Said rotary valve is formed with diametrically opposite wall indentations or recesses 35 registerable respectively with the space 13 and the ports 12 of oppositely related pairs of the cylinders so as to admit fuel charges into the latter at the proper moment according to the firing order, which is 1—2—3—4 in the present instance. Like indentations or recesses 36 diagonally opposed at right angles to the former register respectively with one of the spaces 14 and the aforesaid ports 12 of the oppositely related pairs of cylinders so as to open the latter to exhaust at the proper moments in timing order. In Fig. 3 the valve is shown in position at which intake of the rearmost right-hand cylinder (No. 4) has just been completed and intake of the foremost left-hand cylinder (No. 1) 115 is about to start. In Fig. 4, it is shown in position at which the rearmost right-hand cylinder (No. 4) has just completed its exhaust and the foremost left-hand cylinder (No. 1) is about to begin exhausting. As the pistons have very little motion at top and bottom centers while the valve's rotation is continuous (at half the crank-shaft speed), there is ample time for the cylinder ports to be opened to fuel admission before the pistons travel very far on the intake stroke and ample 125 time for said ports to be opened wide to exhaust before the pistons start upward on the exhaust stroke. This is a very desirable feature as it avoids waste of power from exhausting before the force of combustion is spent.

A heavy film of oil is maintained between the rotary valve and its bore by means of a groove or channel 37 extending the full length of the bore in double return from rear to front at increasing depth as represented. A lead 38 from an oil pump 135 (not shown) opens into this groove by connection at the rear end of the cylinder-block, while the groove discharges through a nozzle or trough 39 at the forward end so as to drain back into the crankcase. The discharging oil is thus advantageously utilized to lubricate the timing-chain and gears encased within a cover-plate 40 bolted to the front end of the cylinder-block. The aforementioned oil pump of course additionally serves the usual purpose of maintaining a pressure circulation of oil through the bearings and other movable parts of the engine.

This mode of lubricating the rotary valve prevents dripping of oil into the combustion chambers of the cylinders, while its location with the

wall of its bore expansively surrounded by cooled water at the low level of pumping into the cylinder-block provides for its effective cooling.

The head applied to the cylinder-block comprises a casting 41 having substantially semi-spherical recesses 42 broadly overlying the cylinder bores and open to the ports (12) thereof in complement of the combustion chambers. Openings 43 to these recesses from the top provide for

10 spark-plugs (not shown) to fire the fuel charges.

A carburetor 44 carried by the head has short manifold connection with a central passage 45 therethrough opening directly into the aforescribed space 13 above the rotary valve, with resultant advantage that the carburetor is virtually the same distance from all cylinders. Lateral passages 46 opening from the other spaces 14 above said valve lead to an exhaust manifold 47 at the side.

20 The head is also formed with water cooling spaces communicating with those in the cylinder-block. Cooling water is introduced through connection 48 with the cylinder-block below the level of the rotary valve and in this instance extending through the timing-chain and gear casting while heated water is carried off through connection 49 with the cylinder head. Circulation of the water is maintained by a water-pump 50 as represented in Fig. 2. A conventional radiator in conjunction with the usual fan is used for cooling the water by air blast.

An improved internal combustion engine is thus provided, which in addition to the advantages already defined has the advantages of a 35 "straight" type motor in simplicity, accessibility and a vertical disposition of the cylinders without its disadvantages of poor carburation and unequal cooling, and the advantages also of the V-type motor in freedom from torsional vibration (because of its short crank-shaft), good carburation and good cooling without the disadvantages of complexity and inaccessibility. Still further, it has the advantages of the so-called 40 "Powell lever motor" with improvements over the latter, particularly in the fact that there are fewer and lighter reciprocating parts than the throw of the crank-shaft.

This engine also embodies the advantages of 50 the rotary valve type of motor with certain improvements, particularly in the adaptation to control the intake and exhaust and also in the location and arrangement for lubrication.

Less important but nevertheless desirable 55 advantages reside in the fact that the engine is also much more compact than the ordinary type of engine having the same number and bore of cylinders or piston displacement, being short and of less height. The employment of a crank-shaft with only one throw for four cylinders or for 60 each group of four cylinders saves much machining and requires less tempering for strength. The entire organization affords material saving in production costs while producing an improved power plant.

65 Since various modifications or changes in the construction and arrangement of parts, with different combinations and sub-combinations may be made without departing from the spirit and scope of the invention, it is not intended that the appended claims shall limit the same to the specific construction shown and described.

Having thus described my invention, what I claim as new and desire to secure by Letters Patent of the United States is:

75 1. In an internal combustion engine, a com-

bined fuel admission and exhaust controlling valve for the cylinders arranged in rows on opposite sides of a center plane; said valve being located between and below the top ends or combustion spaces of the cylinders in parallel relation thereto and to the crankshaft therebelow and comprising a rotatably driven sleeveless body of cylindrical form fitting a bore in the engine casing and having indentations or recesses in its sides alternately according to predetermined timing order opening the intake and exhaust ports of the cylinders to common fuel supply and exhaust passages leading to said bore, and said bore having channels open to oil feed back-and-forth longitudinally with backing to a cooling water space.

2. An internal combustion engine having a combined fuel-admission and exhaust valve in the form of a rotary barrel disposed between adjacent pairs of cylinders and driven by the crank-shaft; said valve being fitted in a tapering bore having connected longitudinal channels for back-and-forth feed of lubricant, and said bore and channels being backed by a cooling water space.

3. In an internal combustion engine embodying 100 a plurality of cylinders, a rotary cylindrical valve controlling the fuel-admission and exhaust of each cylinder disposed in parallel relation to the crank-shaft and driven thereby; said valve being fitted in a bore having lubricant channels running lengthwise thereof in a back-and-forth feed arrangement with connection for continuous lubricant supply, and said bore and channels being backed by a substantially wide water-jacket space.

4. An internal combustion engine, comprising a plurality of cylinders in adjacent row arrangement with a substantially wide cooling medium space between, a combined fuel-admission and exhaust rotary cylindrical valve fitted to a tapering bore within said space at parallel relation to the crank-shaft by which the same is driven, anti-friction mountings for the valve at the ends of said bore, means tensioning the valve longitudinally in snug fit to the bore, and means for a continuous back-and-forth feed of lubricant along the length of the bore; said bore and said feed means being backed substantially widely by said space.

5. An internal combustion engine having a 125 combined fuel-admission and exhaust rotary valve of cylindrical form disposed in a bore between adjacent pairs of cylinders and driven by the crank-shaft; said bore for the valve having a plurality of channels for feed of lubricant to the 130 valve periphery in opposite directions along its length, and said bore and channels being backed by a substantially wide and deep cooling-medium space.

6. In an internal combustion engine, a rotary cylindrical hollow valve-member having closed ends and diametrically opposed longitudinal indentations along the length thereof, a bore in the cylinder casting into which the valve is fitted with said indentations thereof respectively registering 140 as communicating passages between ports of the cylinders and intake and exhaust conduits, lubricant channels in the bore through which oil may be fed in opposite directions from a source of supply, and a cooling-medium space backing said 145 bore and channels.

7. An internal combustion engine comprising 150 multiple cylinders arranged in adjacent rows with a crankshaft journaled intermediately therebelow and a substantially wide water-jacket space

therebetween, a bore in the cylinder casting centrally of said space and parallel to the crank-shaft, a rotary cylindrical valve member fitted into said bore and driven by said shaft, and having indentations in its sides opening intake and exhaust ports of the several cylinders to common fuel supply and exhaust conduits according to predetermined timing order, and channels in said bore for feeding lubricant longitudinally thereof in opposite directions from a supply source; said bore and channels being backed substantially widely by said water-jacket space.

8. In an internal combustion engine, a combined fuel-admission and exhaust rotary cylindrical valve-member controlling all cylinders disposed in parallel relation thereto and driven

by the crank-shaft; said valve having bearing support in a bore of the engine casing formed with a plurality of interconnected channels for feeding lubricant back-and-forth longitudinally, with said bore and channels backed by a water-cooling space. 80

9. In an internal combustion engine, a rotary cylindrical combined fuel-admission and exhaust valve fitting a bore in the engine casing and driven by the crank-shaft; said bore having a plurality of interconnected longitudinal channels for feed of lubricant in opposite directions therealong and backing with said channels to a cooling-medium space. 85
